UNITED STATES PATENT OFFICE

WILLIAM FRANCIS BULL, OF NEW YORK, N. Y.

MAGAZINE PENCIL

Application filed October 12, 1925. Serial No. 61,926.

My invention relates to magazine pencils and refers particularly to a device in which any predetermined crayon of a plurality carried by the device may be presented for use.

- 5 In many kinds of clerical accounting and checking work it is necessary to employ a plurality of different colored crayons, a marking of each color possessing a certain designated meaning.
- 10 It is evident that a single, compact, easily workable pencil carrying a plurality of crayons has many advantages over a plurality of pencils, each one carrying but a single crayon.

The device of my invention is a magazine pencil, or crayon carrier, capable of containing a plurality of crayons, each of which is readily exposed for use, the device having mechanism particularly adapted for exposing any desired length of crayon to compensate for wear, and for other valuable and practical results, all of which will be evident upon a consideration of this specification and the accompanying drawings.

In the accompanying drawings, illustrating modified forms of the device of my invention, similar parts are designated by similar numerals.

Figure 1 is a vertical cross section of one form of my device.

- 30 Figure 2 is a view of the outside tubular casing, partly broken away for purposes of clearness of explanation.

Figure 3 is a view of the inside tubular member, partly broken away for purposes of clearness of explanation.

Figure 4 is a top view of Figure 3.

Figure 5 is a view of the crayon-holder carrier partly in section.

- 40 Figure 6 is a top view of one of the fixed flanges of Figure 5.

Figure 7 is a cross-section through the lines 7-7 of Figure 1 and Figure 5.

Figure 8 is a view of a crayon holder.

- 45 Figure 9 is a cross-section through the lines 9-9 of Figure 8.

Figure 10 is a development showing the groove and tooth construction.

- 50 Figure 11 is a cross-section of a modified form of inner tube.

Figure 12 is a cross-section through the line 12-12 of Figure 11.

The particular form of the device of my invention shown in the accompanying drawings comprises an outer tubular member or casing 11, slideable within which is an inner tubular member 12 extended into the nozzle 13 having an opening 14 therein. The upper portion of the tube 12 has an internally formed regular polygon shape 15, the number of sides of which depend upon the number of crayons to be employed, the top 15 of the shown device being hexagon to accommodate three crayons.

Fixedly attached to the inner face of the 65 casing 11, is a strip of metal 16 having a plurality of parallel grooves 17, 17.

The inner tube 12 has a plurality of parallel grooves 18, 18 corresponding in number and pitch to the grooves 17, 17 of the outer 70 casing 11. The tube 12 has a longitudinal opening 19 so shaped and positioned as to receive the strip 16 of the outer tube 11. A mark 39 is placed on the tube 12 and the lower edge 40 of casing 11 registers therewith when adjusting position of crayons as described later.

Within the inner tube 12, is a crayon-holder carrier comprising the bar 20, which is pointed at its lower end 21, which is capable of partial placement within the nozzle 13. A fixed flange 22 carried by the bar 20, abuts upon the lower face of the flange 23 of the outer casing 11 and a cap 24' is threaded upon the upper portion of the bar 20 and is 80 angularly off-set to rest upon the upper face of the casing 11 or flange 23. It will thus be seen that the bar 20 and the outer casing 11 will move together vertically and that the bar 20 may be revolved independently of the 85 outer casing 11.

The bar 20 has a plurality of channels 24, 24, 24 to receive crayon holders described later. Intermediate between the channels 24, 24, 24 are flat springs 25 so attached that 95 when compressed against the bar 20, they will be flush with the outer intermediate portions 26' of the bar 20. The bar 20 is slideable vertically through the polygon shaped top 15 of the inner tube 12, but not revoluble there- 193

in, unless the crayon carrier and the outer casing 11 are moved along the inner tube 12 until the top 15 of the inner tube 12 is in alignment with the rounded portion 27 of the bar 20, as indicated in dotted lines 15' in Figure 5.

The flange 22 has a plurality of recesses 28, 28, 28 corresponding in number and position to the intermediate sections 26, 26, 26 between channels 24, 24, 24, these recesses allow strip 16 of casing 11 to pass flange 22 when assembling device.

Each crayon holder 29 comprises an upper member 30, having a central slit 31, which acts as a spring, and a plurality of teeth 32, 32 capable of placement within the grooves 17, 17 of strip 16 and the grooves 18, 18 of the inner tube 12. The portion 29 of each crayon holder is extended into a split tubular member 33, 33, having a slit 34 and pointed ends, in order to hold the crayon 35 by spring frictional contact.

The teeth 32, 32 have their ends slightly rounded to insure smooth action. As shown in Figure 10, the grooves 32, 32 of the crayon holders and grooves 17, 17 of strip 16 are of the same shape and pitch. The grooves 18, 18 of the inner tube 12 and the teeth 32, 32 of the crayon holders are of the same pitch but the former are not quite as deep as the latter. This construction is employed to permit a slight clearance in order that the crayon holders will move easily within the inner shell 12 when the bar 20 is revolved.

The grooves 18 at their ends nearest the slot 19 are tapered to the same depth as strip grooves 17 so that the crayon holder teeth 32, 32 will slide easily from engagement with one set of grooves to the other.

The upper portions of the crayon holders are shaped to fit slidably in channels 24 of the bar 20.

The inner tube 12 has openings 36, 36 in the upper portion, so that when it is desired to remove the bar 20, the flat springs 25, 25 may be compressed by passing wires, or other suitable means, through these holes enabling the springs 25, 25 to pass the under edge of the polygon shaped opening 15.

The inner tube 12 has a shallow recess 37 in the upper portion opposite the slot 19 and a similar shallow recess 38 is cut near the top of the strip 16. The object of these recesses is that as the bar 20 is revolved, the top of one of the springs 25 will engage one of these recesses alternately to assist in determining the position of said bar, but not deeply enough to prevent the rotary movement of the bar.

To assemble the device, the bar 20 is inserted in the inner tube 12 through an opening of the polygon shaped top 15 until the rotatable part 27 of the bar 20 is in line with the said top opening, as shown in dotted lines 15', in Figure 5. The bar 20 is then revolved until one of the channels 24 is in line with the slot

19 of the inner tube 12. A crayon holder with crayon is then placed in the channel. The bar is revolved until another channel is aligned with the slot and another crayon holder inserted. This is repeated for the third channel. The bar 20 is then revolved

70

until an intermediate section 26 of the bar is in line with slot 19 and the bar 20 pushed all the way down within the inner tube until the flange 22 rests on the top 15 of the tube 12, the outer casing 11 is then pushed all the way down on inner tube 12 until the flange 23 of the outer casing 11 rests on the flange 22 of the bar 20 and the cap 24 is then screwed into position.

75

In the operation and use of the invention the nozzle end is grasped in one hand and the casing 11 with bar 20 is pulled upward by grasping the cap 24 with the other hand, the upward movement of these parts is checked by the top of flat springs 25 coming in contact with the under edge of regular polygon shaped top opening of inner tube 12, as shown in dotted lines 15' in Figure 5. Then the bar 20 is rotated by means of the cap 24 until the crayon selected to be used is opposite the slot 19 and directly over the opening 14 of nozzle 13 crayon will be visible through part of the slot 19, uncovered by the outer casing in this position, also the engagement of the recess 37 by one of the flat springs 25 will indicate correct position. Then the outer casing 11 is moved downward into position shown in Figure 1 of drawings, causing the crayon holder with its teeth 32 engaged with grooves 17 of strip 16 to slide downward, thus projecting the end of crayon through the nozzle opening ready for use.

80

To select another crayon for use, repeat the operation, rotating the bar 20 until the desired crayon is opposite the slot 19 of inner tube 12.

85

When device is not in use, the above described operation is repeated, except that bar 20 is rotated to bring an intermediate section 26 of bar 20 opposite the slot 19, when the top of one of the flat springs 25 will engage the recess 38 at top of strip 16. When outer casing is then pushed down, no crayons will be projected through nozzle opening, as no crayon holders are engaged with strip 16.

90

The amount of crayon projected through nozzle opening is regulated by shifting the crayon holder up or down to engage its teeth with a higher or lower set of grooves 17 or 18. For this purpose a mark 39 is provided on inner tube 12. To increase the length of projection of crayon, the outer casing 11 with crayon holder and crayon to be adjusted having its teeth 32 engaged with strip 16 is set with lower edge 40 of casing 11 registering with the mark 39, the bar 20 will then be in its rotatable position but lower than its maximum upper position by

95

120

125

130

a distance equal to the pitch of the grooves, then bar is rotated until the crayon holder disengages from strip 16 and engages with grooves in inner tube, it will then be engaged with a lower set of grooves than before, the outer casing with bar is then drawn up to its maximum upper position and the bar again rotated to re-engage the crayon holder with the strip 16 in a corresponding lower set of grooves, outer casing 11 is then pushed down, projecting crayon through nozzle ready for use as before described. This operation may be repeated until crayon is exhausted, the crayon holder will by that time be working in the lowest of the grooves, and must be restored to the upper grooves, and a new crayon inserted. To reduce amount of crayon projected through nozzle opening, the crayon holder must be shifted to engage with higher grooves, the outer casing and bar with crayon holder engaged with strip 16, being first set at its maximum upper position, bar 20 is then rotated to disengage crayon holder from strip 16, then outer casing is set with its lower edge 40 registering with the mark 39 on inner tube, the bar 20 is then rotated to re-engage crayon holder with strip 16 then outer casing 11 is pushed down, projecting the crayon through nozzle a shorter distance than before, this may be repeated as often as necessary until crayon holder is working in the highest grooves.

Fragmentary sectional views of a modified form of inner tube 12 and nozzle 13 are shown in Figures 11 and 12, which may be used if desired to make the nozzle end of pencil appear outwardly more equally centered than before described. Figure 11 shows a cross section of inner tube 12, with its inner circumference and its outer circumference in eccentric relation to each other. The thicker part may be hollow to reduce weight and also to provide a magazine 41 for reserve crayons. The strip 16 is made thicker to correspond with the extra thickness of slot 19. The flange 23 is shaped eccentrically to conform to the shape of the modified form of inner tube 12; the flange 22 on bar 20 and cap 24 are assembled therewith as previously described. Figure 12 is a vertical section taken on the line 12-12 of Figure 11 and shows the nozzle adapted to the modified construction of inner tube as described. All other parts are constructed as previously described and operations are the same.

I do not limit myself to the particular size, shape, number or arrangement of parts as shown and described, as these are given simply as a means for clearly explaining the device of my invention.

What I claim is:

1. In a magazine pencil, in combination, an outer tubular casing; said outer casing

having an internal longitudinal rib having a plurality of transverse grooves; an inner tubular member having an upper interior polygon shape, said inner tubular member having a longitudinal slot in one side and a plurality of annular grooves in its inner wall; means whereby the grooves of the casing and the annular grooves of the inner tubular member may be brought into alignment; a crayon-holder carrier within the inner tubular member; means whereby the carrier and the casing will move together longitudinally with respect to the inner tubular member; means whereby the carrier can be revolved independently of the casing, and means whereby the carrier is slideable through the polygon shaped top of the inner tubular member but locked from revolution therewith.

2. In a magazine, in combination, an outer tubular casing; said outer casing having an internal longitudinal rib having a plurality of transverse grooves; an inner tubular member having an upper interior polygon shape, and having a longitudinal slot in one side and a plurality of annular grooves in its inner wall; means whereby the grooves of the casing and the annular grooves of the tubular member may be brought into alignment; a crayon-holder carrier within the inner tubular member; means whereby the carrier and the casing will move together longitudinally with respect to the inner tubular member; means whereby the carrier can be revolved independently of the casing, means whereby the carrier is slideable through the polygon top of the inner tubular member but locked from revolution therewith and means for unlocking the carrier allowing its revolution within the polygon shaped top of the inner tubular member.

3. In a magazine pencil, in combination, an outer tubular casing; said outer casing having an internal longitudinal rib having a plurality of transverse grooves; an inner tubular member whose inner circumference is in eccentric relation to its outer circumference, having an upper interior polygon shape; said inner casing having a longitudinal slot in one side and a plurality of annular grooves in its inner wall; means whereby the grooves of the casing and the annular grooves of the inner tubular member may be brought into alignment; a crayon-holder carrier within the inner tubular member; means whereby the carrier and the casing will move together longitudinally with respect to the inner tubular member; means whereby the carrier can be revolved independently of the casing; means whereby the carrier is slideable through the polygon top of the inner tubular member but locked from revolution therewith and means for unlocking the carrier allowing its revolution within the polygon shaped top of the inner tubular member.

4. In a magazine pencil, in combination, an outer tubular casing, said outer casing having an internal longitudinal rib having a plurality of transverse grooves; an inner tubular member having an upper interior polygon shape, said inner casing having a longitudinal slot in one side and a plurality of annular grooves in its inner wall; means whereby the grooves of the casing and the annular grooves of the inner tubular member may be brought into alignment; a crayon-holder carrier within the inner tubular member; means whereby the carrier and the casing will move together longitudinally with respect to the inner tubular member; means whereby the carrier can be revolved independently of the casing, means whereby the carrier is slidable through the polygon top of the inner tubular member but locked from revolution therewith, means for unlocking the carrier allowing the revolution with the polygon top of the inner tubular member, a plurality of tubular spring clip crayon holders carried by the carrier and having a plurality of teeth capable of engagement with the grooves of the inner tubular member and the grooves of the casing, and means for alternately engaging the crayon holder teeth with the two series of grooves.
5. In a magazine pencil, in combination, an outer tubular casing, said outer casing having an internal longitudinal rib having a plurality of transverse grooves; an inner tubular member having an upper interior polygon shape, said inner casing having a longitudinal slot in one side and a plurality of annular grooves in its inner wall; means whereby the grooves of the casing and the annular grooves of the inner tubular member may be brought into alignment; a crayon-holder carrier within the inner tubular member; means whereby the carrier and the casing will move together longitudinally with respect to the inner tubular member; means whereby the carrier can be revolved independently of the casing, means whereby the carrier is slidable through the polygon top of the inner tubular member but locked from revolution therewith, means for unlocking the carrier allowing the revolution with the polygon top of the inner tubular member, a plurality of tubular spring clip crayon holders carried by the carrier and having a plurality of teeth capable of engagement with the grooves of the inner tubular member and the grooves of the casing, and means for alternately engaging the crayon holder teeth with the two series of grooves.
6. In a magazine pencil, in combination, an outer tubular casing; said outer casing having an internal longitudinal rib having a plurality of transverse grooves; an inner tubular member having an upper interior polygon shape, said inner casing having a longitudinal slot in one side and a plurality of annular grooves in its inner wall; means whereby the grooves of the casing and the annular grooves of the inner tubular member may be brought into alignment; a crayon-holder carrier within the inner tubular member; means whereby the carrier and the casing will move together longitudinally with respect to the inner tubular member; means whereby the carrier can be revolved independently of the casing, means whereby the carrier is slidable through the polygon top of the inner tubular member but locked from revolution therewith, means for unlocking the carrier allowing the revolution with the polygon top of the inner tubular member, a plurality of tubular spring clip crayon holders carried by the carrier and having a plurality of teeth capable of engagement with the grooves of the inner tubular member and the grooves of the casing, and means for alternately engaging the crayon holder teeth with the two series of grooves.
7. In a magazine pencil, in combination, an outer tubular casing, said outer casing having an internal longitudinal rib having a plurality of transverse grooves; an inner tubular member having an upper interior polygon shape, said inner casing having a longitudinal slot in one side and a plurality of annular grooves in its inner wall; means whereby the grooves of the casing and the annular grooves of the inner tubular member may be brought into alignment; a crayon-holder carrier within the inner tubular member; means whereby the carrier and the casing will move together longitudinally with respect to the inner tubular member; means whereby the carrier can be revolved independently of the casing, means whereby the carrier is slidable through the polygon top of the inner tubular member but locked from revolution therewith, means for unlocking the carrier allowing the revolution with the polygon top of the inner tubular member, a plurality of tubular spring clip crayon holders carried by the carrier and having a plurality of teeth capable of engagement with the grooves of the inner tubular member and the grooves of the casing, and means for alternately engaging the crayon holder teeth with the two series of grooves.
8. In a magazine pencil, in combination, an outer tubular casing, said outer casing having an internal longitudinal rib having a plurality of transverse grooves; an inner tubular member having an upper interior polygon shape; a plurality of annular grooves in its inner surface corresponding to the grooves of the casing; means whereby the grooves of the casing and the annular grooves of the inner tubular member may be brought into alignment.

ment; a crayon-holder carrier within the inner tubular member; means whereby the carrier and the casing will move together longitudinally with respect to the inner tubular member; means whereby the carrier can be revolved independently of the casing, means whereby the carrier is slideable through the polygon shaped top of the inner tubular member but locked from revolution therewith, means for unlocking the carrier allowing its revolution within the polygon top of the inner tubular member, means for limiting the upward movement of the carrier, a plurality of tubular spring clip crayon holders carried by the carrier and having a plurality of teeth capable of engagement with the grooves of the inner tubular member and the grooves of the casing, means for regulating the longitudinal movement of the crayon holders, and means for alternately engaging the crayon holder teeth with the two series of grooves.

9. In a magazine pencil, in combination, an outer tubular casing, said outer casing having an internal longitudinal rib having a plurality of transverse grooves; an inner tubular member having an upper interior polygon shape; a plurality of annular grooves in its inner surface corresponding to the grooves of the casing; means whereby the grooves of the casing and the annular grooves of the tubular member may be brought into alignment; a crayon-holder carrier within the inner tubular member; means whereby the carrier and the casing will move together longitudinally with respect to the inner tubular member; means whereby the carrier can be revolved independently of the casing, means whereby the carrier is slideable through the polygon shaped top of the inner tubular member but locked from revolution therewith, means for unlocking the carrier allowing its revolution within the polygon top of the inner tubular member, means for determining the position of the carrier during its revolution a plurality of tubular spring clip crayon holders carried by the carrier and having a plurality of teeth capable of engagement with the grooves of the inner tubular member and the grooves of the casing, means for regulating the longitudinal movement of the crayon holders, and means for alternately engaging the crayon holder teeth with the two series of grooves.

55 Signed at New York city in the county of New York and State of New York this 9th day of October, 1925.

WILLIAM FRANCIS BULL.
